UNITED STATES PATENT OFFICE.

WILLIAM B. FLEMING, OF DETROIT, MICHIGAN.

ELECTRIC ACTION FOR MUSICAL INSTRUMENTS.

SPECIFICATION forming part of Letters Patent No. 621,963, dated March 28, 1899.

Application filed December 30, 1897. Serial No. 664,572. (No model.)

To all whom it may concern:

Be it known that I, WILLIAM B. FLEMING, a citizen of the United States, residing at Detroit, county of Wayne, State of Michigan, have invented a certain new and useful Improvement in Attachments for Musical Instruments; and I declare the following to be a full, clear, and exact description of the invention, such as will enable others skilled in the art to which it appertains to make and use the same, reference being had to the accompanying drawings, which form a part of this specification.

My invention relates to a novel electric attachment for musical instruments; and it consists of various features embodied in the device shown in the accompanying drawings and hereinafter specified.

In the drawings, Figure 1 is a view in perspective showing features of my invention. Figs. 2 and 2^a are detail views of portions of the mechanism, showing parts in section, Fig. 2 showing parts in horizontal section and Fig. 2^a showing parts in vertical section. Fig. 3 is a side elevation viewed from the side opposite that shown in Fig. 1. Fig. 4 is a view of one of the contact-rollers, showing the shaft in section, together with the adjacent disk-roller. Fig. 5 is a longitudinal section of portions of said disk-roller, showing disks in section. Fig. 6 is a detail view of one of the levers for throwing the driving-shaft out of gear. Fig. 7 is a diagram view showing certain electrical circuits.

My invention is more particularly designed to provide an electric attachment for musical instruments in which plural music-sheets may be employed simultaneously and synchronously actuated.

Parts of the construction embodied in my present construction and in the drawings and specification submitted herewith were also embodied in United States Letters Patent granted to me July 6, 1897, No. 585,663, for an electric attachment for musical instruments. The device set forth in said patent, however, was adapted for operation with a single music-sheet. My present invention contemplates additional mechanism whereby more than one music-sheet may be employed in an attachment of this nature—as, for example, a music-

sheet for a sole and an additional music-sheet for an accompaniment.

In the operation of plural music-sheets it is evident that the sheets must be actuated synchronously or in such a manner that music produced by the sheets shall be in unison or in perfect time, which, obviously, would not result if one of the sheets traveled faster than the other or in such a manner that corresponding perforations in the sheets did not afford synchronous electrical contacts to sound the proper notes in unison. My present invention therefore is designed not only to provide an attachment whereby plural sheets may be employed, but also to provide means for the proper movement of the plural sheets, so that the corresponding notes shall be in unison or in perfect time and any liability of an uneven movement of the sheets avoided or corrected.

I carry out my invention as follows:

A represents any suitable frame constructed to carry perforated music-sheets, two such sheets being shown in the drawings, one at B' and the other at B². The sheet B' is carried upon a drum B.

C denotes a take-up roller upon which the music-sheet B is wound as it unrolls from the drum B. The music-sheet B² is carried upon a drum B². C' denotes an additional take-up roller upon which the music-sheet B² is wound as it unrolls from the drum B² in the use of the instrument.

I will first proceed to describe one of the instruments employed to actuate the first-named music-sheet, which is as follows:

E denotes a metallic contact-roller made of any suitable material, said roller journaled in an oscillatory frame E', said frame made oscillatory in any desired manner, preferably by journaling the lower end thereof upon the shaft of the roller C, so that the roller E may be swung over and downward off from the perforated sheet B', said music-sheet traveling therebeneath in the operation of the device. The frame E' may be provided with a cover portion E² to cover the roller E.

G denotes a contact apparatus or device journaled in suitable bearings upon the frame E' adjacent to the metallic roller E, the music-roll B' traveling between the rollers E and G.

in the operation of the device. The contact apparatus G is formed with a series of disks G', engaged upon the shaft G² of the contact device. The disks G' equal in number the 5 keys upon the keyboard of the musical instrument to which the attachment is applied. This contact device G is similar in construction to the corresponding device embodied in my patent above referred to. To each of said 10 disks G' is led a contact-spring J. The said disks have their outer peripheries in contact with the corresponding roller E when the perforations of the music-sheet B' permit and are preferably provided with hubs g, concaved on 15 their outer peripheries to receive the adjacent end of the corresponding contact-spring J, the concavities serving to hold the corresponding spring in engagement therewith, the springs also exerting a tension to keep the disks up 20 against the roller E, as said springs are preferably engaged in the corresponding concavities on the under side thereof. The disks G' are insulated one from another, as indicated at g', and are mounted upon the shaft G², 25 which is either made of insulating material—as of fiber, for example—or provided with a suitable insulation surrounding the same, (indicated, for example, at G³.) With the several contact-springs J are connected electrical conductors K, leading to a battery, (indicated at II,) a battery-wire K' being connected with the roller E. The frame E' may be made of iron and the battery-wire K' be connected therewith, and so with the roller 30 E. It will be apparent that when the music-sheet B' passes onward between rollers E and G at every perforation of the sheet electrical contact will be formed between the roller E and the corresponding disks of the 35 roller G, completing the electrical circuit and operating the musical instrument accordingly. The conductors K of the two adjacent contact-springs J, I prefer to lead the one upward and the other downward, two rows of 40 binding-posts a and a' upon a portion of the frame being employed simply in order to space the conductors properly apart. Each conductor K, it will be understood, leads to a separate magnet, (indicated at II'.) It will 45 be understood that when a fresh music-sheet is to be put into the device the frame E' will be swung over out of the way. The bore or orifice g² in the disks G', through which the shaft G² is passed, is preferably of larger diameter than that of the shaft, so that the 50 contact-springs may force the disks into contact with the roller E should there be any imperfection or unevenness on the surface of the roller E.

55 In Fig. 3 circuits are shown, as above described, through the rollers E, device G, the spring J, and the corresponding conductors; but it will be understood that each contact-spring J is in a separate circuit similar to that 60 shown in Fig. 3.

65 G⁴ indicates an additional contact device adjacent to the metallic roller F, the device

G⁴ being constructed in a similar manner to the contact apparatus G, with disks insulated one from another and from the shaft of the 70 device G⁴, springs J' being provided to contact with the disks of the device G⁴ in a manner similar to that of the contact of the springs J with the disks of the apparatus G. The perforated music-sheet B² passes between the 75 roller F and the device G⁴, and as the music-sheet travels therebetween electrical contact will be made through the perforations of said music-sheet between the rollers F and the disks of the device G⁴. The springs J' are 80 in electrical contact in a manner similar to the springs J.

K² denotes conductors leading from corresponding springs J' to corresponding magnets H², thence to a battery II³, a conductor K³ 85 leading from said battery to the roller F or to its frame F'.

L denotes a cleaning-roller supported in contact with the apparatus G, as upon a support L', the roller L being preferably covered 90 with chamois-skin and rotatable by frictional contact with the disks of the device G to keep the peripheries of said disks clean. A similar roller L², carried upon a support L³, is arranged in proximity to the device G⁴ to 95 wipe the peripheries of the disks of the device G⁴.

M and M' denote arms fulcrumed to the frame, as at m and m', said arms provided with corresponding springs M² and M³, having 100 frictional contact on the corresponding rollers B and B³, said springs serving to keep the corresponding music-sheets taut when the corresponding rollers E and F are thrown into 105 operative position, said rollers bearing, respectively, in operative position upon the corresponding arms M and M'. When said rollers are thrown back, the pressure on said arms is obviously released, and consequently frictional contact on their respective springs upon 110 their respective rollers.

N represents a spring provided with means at its upper end for engagement therewith of the corresponding frame E'. Said means may consist, for example, of a pin upon the frame 115 E' to engage in a corresponding hole in the upper end of said spring, as indicated at n, whereby said frame is held in position to keep its roller in contact with the disk of the device therebeneath.

I prefer that the drum B should rotate at one extremity upon a cone-pointed shaft b' at one side of the frame, a nut b² holding the shaft b' in place. In a similar manner the roller C is rotatable upon a cone-pointed shaft 125 c' in the side of the frame, a nut c² holding said shaft in place. To actuate the drum B and the roller C, I provide any suitable means. As shown in the drawings, D represents a driving-shaft, to which any desired power may be 130 connected, as by a belt D', said shaft being provided with a driving-pulley d, belted, as by a belt d', with a corresponding pulley b⁵ upon the shaft b of the drum B. By this means the

- drum B and the roller C may be driven to re-
wind the music-sheet B' from said roller to the
corresponding drum. The shaft D is suitably
journaled in the sides of the frame A and at
5 one extremity thereof and is provided with a
pinion, (indicated in Fig. 2^a at P,) the pinion
on the shaft D meshing when in operative po-
sition with a gear C² upon the shaft C³ of the
take-up roller C to drive said storage-roller.
10 The shaft D and its attachments and connec-
tions are shown in detail more particularly in
Figs. 2 and 2^a.

To effect the synchronous travel of the two
music-rolls so that the corresponding notes
15 shall be sounded in unison, additional elec-
trical circuits and devices are employed, which
I will now further describe. The metallic
roller E may be rotatable upon cone-pointed
shafts, (indicated at e.) Said metallic roller
20 is provided with a bushing or sleeve, (indicated
at e'), said bushing or sleeve being insu-
lated from the corresponding roller, as in-
dicated at e².

The numerals 1 and 2 indicate contact-
25 springs in electrical contact with the bushing
e' upon the metallic roller E, while the nu-
meral 3 indicates an additional contact-spring
having direct electrical contact with the me-
tallic roller E, as indicated in Fig. 7.

30 The music-sheet B', in addition to the per-
forations necessary to sound the required
notes, is constructed with a series of elongated
perforations (indicated at 7) and adjacent
smaller perforations, (indicated at 8,) the per-
35 perforations 7 and 8 being indicated in Fig. 7.

Q indicates a magnet which may be located
in any convenient place, while adjacent to the
frame A is an additional magnet Q' to control
the shaft D, and thereby to control the take-
40 up roll C.

Q³ is a binding-post, and Q⁴ the armature
of the magnet Q, an additional post Q⁵ being
in electrical connection with the post Q³, the
armature Q⁴ contacting with the post Q⁵ when
45 open. The armature Q⁶ of the magnet Q' is
provided with a yoke (indicated at Q⁷) at its
opposite end. A yoke R is secured to the
frame in which the armature Q⁶ is fulcrumed.

Upon the shaft D is a disk 11, rotatable with
50 the shaft. The disk 11 may be held upon the
shaft D in any suitable manner, as by a pin
d¹, a collar d² being provided on said shaft on
the inside of the case. Upon said shaft is
also located a movable friction-pulley 12, con-
55 structed to have frictional contact with the
disk 11 and to be thrown out of frictional en-
gagement with said disk. The hub 13 of the
friction-pulley 12 is constructed with an an-
nular groove 14, with which groove the yoke
60 Q⁷ is engaged, as by screw-studs 15, engaged
in said yoke and projecting into said groove.
A tension-spring 16 is located upon the shaft
D outside the hub 13, said spring normally
65 serving to hold the friction-pulley 12 in fric-
tional contact with the disk 11. A thumb-
nut 17 or analogous device bears against one
end of the spring and provides means for

regulating the tension of the spring. It will
be evident that when the armature Q⁶ is at-
tracted to its magnet the yoke end Q⁷ will
70 throw the friction-pulley 12 out of frictional
contact with the disk 11, in consequence of
which the shaft D will cease to rotate and
the travel of the corresponding take-up roller
will stop.

75 The other instrument, located toward the
lower portion of the frame, is similar in con-
struction to the instrument hereinbefore de-
scribed.

F denotes a metallic contact-roller similar
80 in construction to the roller E, said roller F
being journaled in an oscillatory frame F',
preferably journaled upon the shaft of the
roller C' and provided with a cover portion
F², the perforated music-sheet B² traveling
85 under the metallic roller F in the operation of
the machine. This roller F may also be swung
over and downward and away from the un-
derlying music-sheet.

N' represents a spring similar to the spring
90 N for engagement therewith of the frame F',
said spring provided with a hole in the upper
end thereof, (indicated at n'.)

The drum B³ may rotate at one end upon a
cone-pointed shaft b³ in the frame, a nut b⁴
95 holding said shaft in place. Likewise the
roller C' may be rotatable at one end upon a
cone-pointed shaft c³, held in place by a nut
c⁴. The drum B³ and take-up roller C' may
be driven in a similar manner to the drum B,
100 a shaft D² being provided, to which any de-
sired power may be connected, as by a belt
D³. The belts D' and D³ are engageable, re-
spectively, with pulleys 12 and 18. The shaft
D² may also be provided with a pulley d²,
105 similar to the pulley d, belted, as by a belt
d³, to a pulley b⁶, similar to the pulley b⁵ upon
the shaft b⁷ of the drum B³. The shaft D² is
also provided with a pinion P, said latter pin-
ion actuating a toothed gear C⁴ upon a shaft
110 of the take-up roller C'. It will be under-
stood that the shaft D² and its attachments
and connections are every way similar to the
shaft D and its attachments and connections
and therefore need not be separately illus-
115 trated and described. The metallic roller F
may also be rotatable upon cone-pointed
shafts, (indicated at f,) said roller being pro-
vided with a bushing or sleeve, (indicated at
f'), insulated from the corresponding roller,
120 as indicated at f². Both contact metallic rolls-
ers E and F are preferably negative in their
electrical connections.

Contact-springs (indicated by the numerals
4 and 5) similar to the springs 1 and 2 are in
125 electrical contact with the bushing f' upon
the roller F, while an additional contact-
spring (indicated by the numeral 6) corre-
sponding to the spring 3 is in direct electrical
contact with the roller F. So, also, the music-
sheet B², in addition to the perforations nec-
essary to sound the required notes, is con-
structed with elongated perforations 9 and
adjacent smaller perforations 10, said latter

perforation indicated also in Fig. 7. These latter perforations in the music-sheets are so located that the corresponding contact-springs 2 3 and 5 6 may make electrical contact therethrough when said perforations 7 8 and 9 10 are adjacent to the corresponding rollers E and F.

It will be observed that the springs 1 2 and 4 5 are in electrical contact with the corresponding bushings, while the springs 3 and 6 are in electrical contact with the corresponding metallic rollers insulated from said bushings.

Adjacent to the frame is an additional magnet Q³ to actuate the shaft D², and thereby to control the take-up roller C'.

By reference to the diagram view in Fig. 7 the electrical circuits in which the contact-springs 1, 2, 3, 4, 5, and 6, together with their corresponding rollers and the magnets, may readily be traced. The contact-springs 1 and 4 are connected by conductors, as indicated by the arrow-heads, with the battery II, the battery II being connected by a suitable conductor with the frame of the device. The springs 2 and 5 are connected by conductors (indicated by the double arrow-heads) with the magnet Q and armature Q⁴ and with the battery II. The springs 3 and 6 are connected by conductors (indicated by the triple arrow-heads) with the magnets Q' Q² and through their respective rollers E and F with the battery II. The armature Q⁸ of the magnet Q³ is provided with a yoke Q⁹ at its opposite end.

R' is a yoke similar to the yoke R, secured to the frame in which the armature Q⁸ is fulcrumed.

The shaft D², it will be understood, is similarly provided with a friction-pulley 18, engageable with a disk rotatable with a shaft D², the disk on the shaft D² not being shown, but being analogous to the disk 11 on the shaft D. The hub 19 of the friction-pulley 18 is also provided with an annular groove (indicated at 20) in which screw-points 21 in the yoke Q⁹ project, and it will be understood the outer end of the shaft D² is also provided with a spring analogous to the spring 16 to throw the friction-pulley 18 normally into engagement with its corresponding disk to actuate the shaft D². It will be obvious that when the armature Q⁸ is attracted to its magnet the yoke end of said armature will throw the friction-pulley 18 out of frictional contact with its corresponding disk, causing the shaft D² to cease its rotation, and consequently stop the travel of the take-up roller C'.

The elongated perforations 7 and 9, it will be observed, project in advance of the perforations 8 and 10, so that electrical contacts may be made through the perforations 7 and 9 in advance of the electrical connections made through the perforations 8 and 10. The perforations 7 and 9 are provided in order to cut out the circuits in which the springs 3 and 6 are interposed from the two magnets Q' and

Q², which control the operation of the two take-up rollers, if required.

In the operation of the device the springs 2 and 5 will form contact with the corresponding bushings or sleeves first or before any contact may be formed by the springs 3 and 6 through the perforations 8 and 10. When the contacts are made through the perforations 7 and 9, the corresponding conductors are cut out from the two magnets Q' and Q². If the two music-sheets are traveling together in proper manner, the contacts made through the elongated perforations 7 and 9 simply cut out the corresponding conductors from said magnets which control the traveling of the music-sheets and nothing results; but if either one of the elongated perforations 7 and 9 is traveling ahead the one of the other it will be seen that contacts will be made by the corresponding springs through the perforations 8 and 10 to actuate the magnets Q' and Q² and to throw the corresponding friction-pulleys out of contact with the corresponding friction-disks, thereby stopping the travel of the sheet which is traveling ahead of the other, the sheet so stopped being held from moving until the other sheet catches up or until contacts are made through the perforations 7 and 9, cutting out the corresponding conductors from the corresponding magnets and allowing the music-sheet that has been stopped to travel onward. Thus when contacts are made through the two elongated perforations—that is, when said elongated perforations are in corresponding line or position and contacts made therethrough—the magnets Q' and Q² are cut out, and consequently the corresponding friction-pulleys are left in frictional contact with their respective disks. The perforations 7 and 9 should be sufficiently elongated to insure electrical contacts therethrough prior to electrical contacts through the perforations 8 and 10, so as to cut out the circuits in which the springs 3 and 6 are interposed when the parts are in proper relative position, and to secure the desired results the perforations 7 and 9 should be of a length about twice the diameter of the perforations 8 and 10. The springs 1 and 4 are in contact with the corresponding bushings outside the music-sheets and keep the corresponding bushings in electrical circuit all the time. Thus the friction-pulleys are moved away from their corresponding friction-disks when the circuit is completed through the smaller perforations 8 and 10; otherwise the corresponding springs hold said friction-pulleys in frictional contact with the corresponding disks to turn the take-up rollers.

Upon each of the two shafts D and D² at one side of the device is a sleeve V, made reciprocatory on its shaft, said sleeve provided at one end with the corresponding pinion P to mesh with the gear upon the shaft of the corresponding take-up roller. Said sleeve

may be constructed with a slot or orifice V' , into which projects a pin V^2 upon the adjacent shaft to limit the reciprocation of the sleeve. The sleeve is also constructed with an 5 annular groove at V^3 and is constantly driven by the shaft D by means of the pin V^2 through the orifice V' .

T is a lever fulcrumed, as at t, to any suitable portion of the frame, as upon an arm T' , 10 secured to the frame A. This lever, as indicated in Fig. 6, is beveled at one end, as indicated at t' . A lever T is located to engage each of the shafts D and D^2 in the manner hereinbefore described, said levers provided 15 at the end opposite the beveled edge t' with a pin t^2 to project into the annular groove V^3 of the corresponding sleeve, as shown more particularly in detail in Figs. 2 and 2^a. Each of the frames E' and F' toward its lower end 20 is provided with a pin t^3 . This pin is so located that when the corresponding frame is swung over and away from the music-sheet, the pin t^3 will contact with the beveled edge of the corresponding lever T, thereby oscillating 25 said lever on its fulcrum t, as indicated in dotted lines in Fig. 6, by which means the corresponding sleeve is moved on its shaft to throw its pinion out of mesh with the corresponding gear, thereby causing the rotation 30 of the corresponding take-up roller to cease, whereby the mechanism is free to rewind, as hereinafter described. Each of the shafts D and D^2 is also provided with a disk V^4 , provided with a pin V^5 , projecting inward, while 35 the corresponding sleeve at the end adjacent to said disk is provided with a pin V^6 , projecting toward the pin V^5 . It will be observed that when the pinion is in mesh with the corresponding gear the pins V^5 and V^6 are separated 40 so as to pass one another without contact; but when the pinion is moved away and out of mesh with its corresponding gear the pin V^6 upon the sleeve is moved so as to contact with the pin V^5 in the rotation of the 45 corresponding shaft. The pulleys d and d^2 upon their corresponding shafts, together with the corresponding disks V^4 , respectively, are rigidly connected, and when the pinion is in mesh with the corresponding gear the 50 corresponding pulley is loose upon the shaft; but when the pin V^6 contacts with the pin V^5 , as above specified, the disk and pulley will be rotated, driving the corresponding belt d' or d^2 to rewind the music-sheet upon its corresponding drum B' or B², when the corresponding frame E' or F' is thrown over.

It will be evident that the parts provided with the pins V^5 and V^6 constitute a clutch mechanism, and that any suitable clutch 60 mechanism may be substituted therefor.

The note-perforations in the music-sheets, or perforations through which contacts are made to sound the notes, are indicated at 22.

Both contact devices are constructed not 65 only with a series of disks G' equal to the number of notes to be sounded and upon which contact-springs J and J' have contact, but with

two outside disks G⁵ G⁶, with which the corresponding contact-arms 2 3 and 5 6 are in contact, as illustrated more particularly in Fig. 5, the arms 1 and 4, as already observed, being outside the edge of the music-sheet and not needing to contact with any insulated disks upon the corresponding contact device. The arms 2 3 and 5 6 preferably have contact 75 in hubs of the corresponding disks in a manner similar to the springs J and J'. The arms 3 and 6 preferably contact with the body of the contact devices E and F, as thereby different voltages may be given to said rollers, 80 if desired, from that supplied to the bushings or sleeves upon said roller. As shown, the rollers E and F are both negative, as indicated by the negative sign therebeneath in Fig. 7.

The elongated perforations 7 and 9 are employed in order that they may extend in advance of the corresponding perforations 8 and 10 and to the rear thereof, and thereby prevent electrical contacts first being made through said perforations 8 and 10 when the 90 music-sheets are traveling in unison. It will be observed that if the contact-springs 2 and 5 make electrical connection through the perforations 7 and 9 first the springs 3 and 6 would be cut out, which operation will take 95 place where the sheets are traveling in unison. The elongated perforations should be of such a length as to permit their projecting forward of the smaller perforations 8 and 10 to allow the cutting out of the springs 3 and 6, as above described, and should also project sufficiently to the rear of the perforations 8 and 10 to hold the springs or contacts 3 and 6 cut out until the sheets have passed the points of contact of said springs through their 105 corresponding perforations. If the sheets are traveling in unison, then of course the perforations 7 and 9 are in unison and electrical circuits are established with the two magnets that actuate the clutches. The perforations 110 8 and 10 are only about one-eighth of an inch in diameter, and it will be seen that the sheet has to travel but a very short distance before the perforations are past the springs 3 and 6. It will also be understood that the sheets are 115 traveling quite rapidly and that the electrical contacts are consequently very quick and short. If the sheets vary but a little, any variance in the notes would not be noticed, because the electrical contact is so quickly terminated; but if one sheet traveled so far ahead of the other that the proper contacts should not be formed in time to cut out the springs 120 3 and 6, the travel of said sheet would be simply stopped until the other sheet caught up 125 again. The corresponding clutch might be operated just for an instant. The action must be very quick and brief to accomplish the desired result. The action of the sheets does not have to be perfectly simultaneous, as but 130 a slight difference cannot be detected.

What I claim as my invention is—

1. A music-sheet provided with two series of perforations to regulate the travel of the

sheet, said perforations arranged in adjacent pairs, one perforation of each pair being elongated and projecting forward of the corresponding perforation, for the purpose set forth.

2. In an electrically-controlled attachment for musical instruments, a music-sheet provided with perforations arranged in pairs, whereby the travel of the sheet may be regulated, one perforation of each pair extending in advance of the other, whereby an electrical circuit may be closed through one of said perforations of each pair before a circuit may be closed through the other perforation of each pair, as set forth.

3. In an attachment for musical instruments, two music-sheets provided with perforations whereby the travel of the sheets may be regulated to keep the sheets in unison, metallic contact-rollers each provided with a contact-sleeve, contact-springs to contact with said rollers and contact-springs to contact with said sleeves, electrical circuits connected with said contact-springs, and magnets interposed in said circuits, for the purpose set forth.

4. In an attachment for musical instruments, two music-sheets provided with two series of perforations, whereby the travel of the music-sheets may be regulated to keep them in unison, metallic contact-rollers each provided with an insulated sleeve, electrical circuits connected with said rollers and with said sleeves, contact-springs in said circuits to form electrical contact through said perforations, and magnets interposed in said electrical circuits, for the purpose set forth.

5. In an attachment for musical instruments, two music-sheets provided with perforations whereby the travel of the sheets may be regulated to keep them in unison, metallic contact-rollers each provided with an insulated sleeve, contact-springs to contact with said sleeves, electrical circuits connected with said springs and with said rollers, and magnets interposed in said circuits, for the purpose set forth.

6. In an attachment for musical instruments, a music-sheet having note-perforations, and additional series of perforations for the purpose set forth, a contact apparatus provided with a series of disks equal in number to the rows of note-perforations of the music-sheet, and with additional insulated disks equal in number to said additional perforations of the music-sheet, and electrical circuits provided with means to form electrical contacts through said perforations, said perforations arranged in pairs, one perforation of each pair being elongated and projecting forward of the corresponding perforation, substantially as described.

7. In an attachment for musical instruments, a traveling music-sheet provided with note-perforations and with additional perforations arranged in pairs to regulate the travel of the sheet, a contact-roller, a contact apparatus provided with a series of insulated disks

equal in number to the rows of note-perforations of the music-sheet, and with additional insulated disks equaling the number of regulating-perforations of the music-sheet, contact-springs in electrical connection with said disks, electric circuits in electrical connection with said contact-roller and with said contact-arms, and electrically-controlled means interposed in said circuits to regulate the travel of the sheet, said perforations arranged in pairs, one perforation of each pair being elongated and projecting forward of the corresponding perforation, substantially as described.

8. In an attachment for musical instruments, two independently-traveling music-sheets each provided with two series of perforations arranged in adjacent pairs, one perforation of each pair being elongated and projecting forward of the corresponding perforation, and electrically-actuated means arranged to regulate the travel of said sheets to cause said sheets to operate in unison, substantially as set forth.

9. In an attachment for musical instruments, two traveling music-sheets each provided with two series of perforations arranged in pairs, one perforation of each pair being elongated and projecting forward of the corresponding perforation, independent shafts to drive said sheets, and electric means arranged to regulate the operation of each of said shafts to cause the music-sheets to operate in unison, substantially as set forth.

10. In an attachment for musical instruments, two independent drums, corresponding take-up rollers, two independently-traveling music-sheets carried upon said drums and take-up rollers, each sheet provided with note-perforations and with additional perforations arranged in pairs, and electrical means arranged to regulate the travel of said sheets to cause them to operate in unison, substantially as set forth.

11. In an attachment for musical instruments, two traveling music-sheets each provided with note-perforations, and with additional series of perforations arranged in pairs, independent shafts to drive said sheets, clutch mechanism to drive each of said shafts, and electric means arranged to actuate the clutch mechanism to regulate the travel of the music-sheets, substantially as set forth.

12. In an attachment for musical instruments, the combination of two music-sheets each provided with two series of perforations arranged in adjacent pairs, one perforation of each pair being elongated, independent traveling drums and corresponding traveling take-up rollers to carry said music-sheets, an oscillatory frame provided with a contact-roller adjacent to each music-sheet, a conductor in electrical connection with each of said contact-rollers, a shaft provided with a series of insulated disks adjacent to each of said contact-rollers, and between which and the corresponding contact-roller one of the music-sheets passes, contact-springs in electrical

connection with each of said series of disks, and electrically-controlled means arranged to regulate the travel of said music-sheets to cause said sheets to operate in unison, substantially as set forth.

13. In an attachment for musical instruments, two music-sheets each provided with two series of perforations arranged in adjacent pairs, one perforation of each pair being elongated, independent drums upon which said music-sheets are placed, independent take-up rollers upon which the music-sheets are wound in the action of the device, means to actuate said take-up rollers, a contact-roller adjacent to each of the music-sheets, a series of insulated disks adjacent to each of said contact-rollers, and between which and the corresponding contact-roller one of the music-sheets passes, an insulated shaft upon which said disks are mounted, contact-springs in electrical connection with said disks, said springs and contact-rollers provided with electrical conductors, and electrically-controlled means arranged to regulate the travel of each of said music-sheets, for the purpose set forth.

14. In an attachment for musical instruments, the combination of two music-sheets each provided with two series of perforations arranged in adjacent pairs, one perforation of each pair being elongated, independent drums and corresponding take-up rollers to carry said music-sheets, a contact-roller for each of said sheets, a series of insulated disks adjacent to the corresponding contact-roller to contact with the adjacent roller through the note-perforations of the music-sheet, contact-springs in connection with said disks, electrical conductors leading to each of said contact-rollers and to each of said disks, and electrically-controlled means arranged to regulate the travel of said music-sheets, for the purpose set forth.

15. In an electrically-controlled attachment for musical instruments, a music-sheet provided with note-perforations and with two additional series of perforations arranged in pairs through which the electric circuit is closed to regulate the travel of the sheet, one perforation of each pair being elongated, as set forth.

16. In an attachment for musical instruments, music-sheets each provided with two series of perforations arranged in adjacent pairs, one perforation of each pair extending in advance of the other to regulate the travel of the sheets, independent traveling drums and corresponding take-up rollers to carry said music-sheets, shafts to actuate the take-up rollers, clutch mechanism upon each of said shafts, electric circuits, and a magnet provided with an armature arranged to actuate each of the clutch mechanisms, said magnet controlled by said perforations, substantially as described.

17. In an attachment for musical instruments, two music-sheets each provided with

two series of perforations arranged in adjacent pairs, one perforation of each pair extending in advance of the other to regulate the travel of the sheets, independent traveling drums and corresponding take-up rollers to carry said sheets, a shaft to actuate each of said sheets, clutch mechanism upon each of said shafts, an electric circuit, an armature in said circuit to actuate each of said clutch mechanisms, a magnet in said circuit to actuate each of said armatures, and electrically-actuated devices to throw said magnet into and out of operation, said devices controlled by said perforations, substantially as set forth.

18. In an attachment for musical instruments, music-sheets each provided with two series of perforations arranged in adjacent pairs, one perforation of each pair extending in advance of the other to regulate the travel of the sheets, independent shafts to drive said sheets each provided with clutch mechanism, an armature fulcrumed intermediate its ends, and provided with a yoke at one end to actuate the clutch mechanism, and a magnet to actuate said armature, said magnet controlled by said perforations, substantially as set forth.

19. In an attachment for musical instruments, the combination of a music-sheet, a drum and a take-up roller to carry said sheet, a shaft to actuate said take-up roller, means to govern the operation of the take-up roller, an oscillatory frame, a pinion upon said shaft to actuate the take-up roller, a pulley upon said shaft to drive said drum, a lever actuated by the movement of said frame to throw said pinion out of operation with the take-up roller, and into operation with said pulley to rewind the music-sheet upon said drum, substantially as set forth.

20. In an attachment for musical instruments, the combination of music-sheets, a drum and a take-up roller to carry each of said music-sheets, driving-shafts, a pinion upon each shaft geared with the corresponding take-up roller, an electrically-controlled clutch on each driving-shaft, electrically-governed means controlled by the travel of said sheets to govern the operation of the driving-shafts, a pulley upon each of the driving-shafts and upon the shaft of each of said drums, a belt upon each of said pulleys, an oscillatory frame, a lever actuated by said frame to throw each of the driving-shafts out of gear with the corresponding take-up roller and to actuate the pulley upon the corresponding driving-shaft to rewind the music-sheet upon the drum, substantially as set forth.

21. In an attachment for musical instruments, the combination of music-sheets each provided with a series of perforations to regulate the travel of the sheets, drums, and a take-up roller to carry each of the music-sheets, driving-shafts, electrically-governed means controlled by the travel of said sheets to govern the operation of the driving-shafts,

a gear upon the shaft of each of the take-up rollers, a sliding sleeve upon each driving-shaft provided with a pinion meshing with said gear to drive the corresponding take-up roller, means to reciprocate said sleeve to throw said pinion out of mesh with said gear, a pulley upon each driving-shaft and upon the shaft of each of the drums, and a clutch actuated by the movement of said sleeve when its pinion is thrown out of gear to actuate the pulley upon each of the driving-shafts to rewind the music-sheets, said perforations arranged in pairs, one perforation of each pair being elongated to extend in advance of and rearward of the other, substantially as described.

22. In an attachment for musical instruments, the combination of traveling music-sheets each provided with two series of perforations to regulate the travel of the sheets, drums, take-up rollers to carry the music-sheets, driving-shafts, a clutch on each driving-shaft, electrically-governed means controlled by the travel of said sheets to govern the operation of the driving-shafts, sliding sleeves upon the driving-shafts geared with the corresponding take-up roller, pulleys upon the driving-shafts and upon the shafts of the drums, belts uniting corresponding pulleys, oscillatory frames, and levers actuated by the movement of said frames to actuate said sleeves, said perforations arranged in adjacent pairs, one perforation of each pair extending in advance of the other, substantially as described.

23. In an attachment for musical instruments, two independently-traveling music-sheets each provided with note-perforations and with additional perforations arranged in pairs, one perforation of each pair being elongated to project forward and rearward of the corresponding perforation, and electrical mechanism controlled by said perforations to regulate the travel of said sheets, substantially as set forth.

24. In an attachment for musical instruments, two traveling music-sheets each provided with note-perforations, and with an additional series of perforations arranged in pairs, one perforation of each pair being elongated to project forward and rearward of the corresponding perforation, independent shafts to drive said sheets, clutch mechanism to drive each of said shafts, and electrically-

actuated means arranged to operate the clutch mechanism, said means forming electrical contacts through the additional perforations in said sheets to regulate the travel of the sheets, substantially as set forth.

25. In an attachment for musical instruments, two music-sheets each constructed with note-perforations and with additional perforations arranged in pairs, one perforation of each pair being elongated to project forward and rearward of the corresponding perforation, independent traveling drums and corresponding take-up rollers to carry said sheets, two shafts each provided with a series of disks insulated one from another, a contact-roller adjacent to the disks upon each of said shafts between which and the adjacent disks the corresponding music-sheet passes, a conductor in electrical connection with each of said contact-rollers, contact-springs in electrical connection with each series of said disks, and electrically-controlled means governed by said perforations arranged to regulate the travel of said music-sheets to cause said sheets to operate in unison, substantially as set forth.

26. A music-sheet provided with two series of perforations to regulate the travel of the sheet, one perforation of each pair being elongated, electric contacts arranged to be closed through said perforations, and whereby an electric contact may be closed through the elongated perforations in advance of an electric contact being made through the other corresponding perforations, substantially as set forth.

27. In an attachment for musical instruments, means to effect the travel of the music-sheet, a music-sheet provided with two series of perforations arranged in pairs, and electric contact devices arranged to be closed through said pairs of perforations, whereby an electrical contact may be formed through one perforation of each of said pairs in advance of the electrical contact made through the other corresponding perforation and subsequent thereto to regulate the travel of the music-sheet, substantially as described.

In testimony whereof I sign this specification in the presence of two witnesses.

WILLIAM B. FLEMING.
